UNITED STATES PATENT OFFICE.

EDWARD MYERS, OF JOPLIN, MISSOURI, ASSIGNOR TO SARAH E. MYERS, OF SAME PLACE.

SAFETY-GUARD FOR RAILWAY-CARS.

SPECIFICATION forming part of Letters Patent No. 245,389, dated August 9, 1881.

Application filed February 24, 1881. (Model.)

To all whom it may concern:

Be it known that I, EDWARD MYERS, of Joplin, in the county of Jasper and State of Missouri, have invented certain new and useful Improvements in Safety-Guards for Railway-Cars; and I do hereby declare the following to be a full, clear, and exact description of the invention, such as will enable others skilled in the art to which it pertains to make and use it, reference being had to the accompanying drawings, which form part of this specification.

My invention relates to an improvement in safety-guards for railway-cars, the objects of the same being to provide means for retaining the cars on the track when an axle or rail has been accidentally broken, and to prevent the tipping over of the cars when exposed to severe gales.

With these ends in view my invention consists in certain details in construction and combinations of parts, as will be more fully explained, and pointed out in the claims.

In the drawings, Figure 1 is a side view of a car-truck provided with my improved guards. Fig. 2 is a front view of the same. Fig. 3 is a detail view of one of the safety-guards. Fig. 4 is a view of the improved switch. Fig. 5 is a view of the manner of connecting the rails. Fig. 6 is a modification of the guard, and Fig. 7 shows the manner of connecting the rails.

A is the truck-frame, of the ordinary construction, supported on axles B and wheels C. From the ends of transverse beams d of the truck-frame A are suspended the hanging arms D, having lateral projecting flanges a at their upper end. These flanges a are provided with bolt-holes b, through which the fastening-bolts c pass and secure the hanging arms D in place on the transverse beam d by a nut screwed on the projecting end of bolt c. These hanging arms D are strengthened by braces d', and suspended over the rails E, and have the guards F pivotally secured thereto at their lower end. The guards F are composed of two faces, e e', formed precisely alike, and arranged one on each side of the rail, and adapted to envelop the tread thereof and pre-

vent the truck from leaving the rail in case of an accident to the truck itself or by misplacing a switch.

The guards can be made in a variety of ways to accomplish the same result, it only being necessary to have the face or faces of the guards so arranged to move laterally outward, or one face removably secured to the other to allow the guards to be applied around the head of the rail while the truck is standing thereon, which result could not be accomplished if the faces of the guards were constructed of one piece of metal.

One manner of accomplishing the above result is shown in Fig. 3. The faces are composed of two distinct parts, the face e being pivotally secured to the lower end of the hanging arm, and having two lugs, f, projecting from the upper side thereof, which abut against the projecting pin or stop g on the hanging arm, thereby limiting the rotary movement of the guards. The lower end of face e is curved inwardly, forming projecting lips h, which, in conjunction with the projecting lip of the companion face e', form a passage-way of less diameter than the tread of the rail, thereby preventing its withdrawal therefrom, but leaving sufficient space for the web of the rail to pass through without impinging on the projecting lips h. The other face, e', is shaped like the face e, and is secured to the top thereof in any desired manner. A longitudinal slot, h', is formed therein, which allows the plate e' to be placed in position on the companion plate e, where it is secured by screws passing through both plates. The lugs f of plate e pass up through the longitudinal slot h' in plate e' and assist in holding the upper plate in position when the guard comes in contact with an obstruction.

It will be seen from the above that when it is desired to place the guard in position on the rail it will only be necessary to place the top plate, e', in position on the plate e and secure it thereto by the screws; and when it is desired to remove it to simply remove the screw, when the top plate, e', can be removed therefrom. Another mode of constructing the guard would be to have one face hinged to the

companion face, and to swing laterally outward, as shown in Fig. 6, the jaws being held in position by bolts passing through the plates, said bolts having shoulders which abut against 5 the inner faces of the plates, and provided with screw-threaded ends, on which nuts are screwed to hold the bolts in place.

The projecting lips *h* of the plates *e e'* are beveled at both the front and rear ends, which 10 forms a flaring opening with inclined sides, which operates to correct misplaced switches and prevent the ends or corners of the projecting lips from impinging on the web of the rail in turning curves.

15 In using my improved guard it will be necessary to dispense with the frogs ordinarily used in switching, and for this purpose I have devised a switch, to be used in conjunction with my improved guard, which allows the 20 guard to pass unobstructed onto a siding.

The switch shown in Fig. 4 of the drawings is the same as the switch ordinarily used, except that the frog is removed and in its stead are two parallel rails, which are moved by a 25 switch-bar, so as to adjust the truck either to the main or switch track. This switch is composed of two sections, *A' B'*. In the section *A'* are shown two main rails, *a' a²*, and two switch-rails, *b' b²*. These rails are all pivoted 30 to the cross-tie *c'*, while their opposite ends rest upon the bearing *d'*, adapted to have a lateral sliding movement between the guides *n n'*.

To the outer end of bearing *d'* switch-lever 35 *p* is attached, by which the rails are operated and locked in position.

The second section of the switch consists of the main rails *a³ a⁴* and two switch-rails, *b³ b⁴*. The main rail *a³* and switch-rail *b⁴* are firmly 40 secured in place, while the main rail *a⁴* and switch-rail *b³* are adapted to be operated by the switch-lever *p'*. These rails *a⁴* and *b³* are pivotally secured at one end to cross-tie *c²*, while their opposite ends rest on the cross-tie 45 *c*, and are operated together by a connecting-rod, *d³*, secured to the under side of the rails, and having a switch-lever, *d⁴*, secured thereto, which effectually holds the rails in place.

By means of this improved switch I dispense with the frogs ordinarily used and avoid 50 crossing tracks, both of which would interfere with the operation of my improved guard, and use rails which are adapted to be moved in position as required.

55 In some instances it will be necessary to provide improved fastenings for the meeting ends

of the rails, as the means now employed therein would obstruct the free passage of the guards; and to overcome this I mortise one end of the rail, as at *s*, and form corresponding projections *r* in the opposing face of the meeting-rail, which fits in said mortise and prevents the rails from diverging from their course, while at the same time they are held firmly in place by the plates *t t'*, placed respectively above and below the flange of the rail.

When it is necessary that one track should cross another track a turn-table having two rails placed thereon is introduced at the crossing, which is used for both tracks, and allows the guards to pass over unobstructed.

It is evident that slight changes in the construction might be resorted to without departing from the spirit of my invention, and hence 75 I would have it understood that I do not confine myself to the exact construction shown and described; but,

Having fully described my invention, what I claim as new, and desire to secure by Letters 80 Patent, is—

1. The combination, with a truck-frame, of depending arms *D*, rigidly secured at their upper ends to the truck-frame, and having a safety-guard swiveled upon their lower ends, said 85 safety-guard composed of two sections, constructed to be separated, to be placed over the tread of the rail, and then bolted together, substantially as set forth.

2. The combination, with a truck-frame, of 90 depending arms *D*, rigidly secured at their upper ends to the truck-frame, each having a guard swiveled upon its lower end, said guard consisting of two curved plates, *e e'*, plate *e* being swiveled upon the rod *D* and plate *e'* 95 constructed with an open slot, *h'*, and bolted to plate *e*, substantially as set forth.

3. The combination, with a truck provided with swiveled safety-guards constructed to extend below and beneath the rail-treads, of a 100 switch composed of switch-section *A'*, consisting of the rails *a' a² b' b²*, pivoted at one end and provided with a connecting-lever at their opposite ends, substantially as set forth.

In testimony that I claim the foregoing I 105 have hereunto set my hand this 9th day of February, 1881.

EDWARD MYERS.
